UNITED STATES PATENT OFFICE

WILLIAM A. STELLING, OF PROVIDENCE, RHODE ISLAND, ASSIGNOR TO THE TEXTILE-FINISHING MACHINERY COMPANY, A CORPORATION OF RHODE ISLAND

TENTER CHAIN LINK

Application filed September 8, 1930. Serial No. 480,408.

This invention relates to a tenter chain link; and has for its object to provide a manually detachable work engaging blade on the movable jaw.

A further object of this invention is the provision of means for positively and pivotally supporting the work engaging blade and yet permitting it to be removed by simple manual manipulation or movement of the mounting means to a predetermined detaching position.

A still further object of this invention is the provision of means for positively locking the mounting means in working position.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a face view or front elevation of one of the tenter chain links;

Fig. 2 is a central section thereof on line 2—2 of Figure 1;

Fig. 3 is a sectional view through the movable jaw showing the work engaging blade or insert as mounted therein in working position;

Fig. 4 is a view similar to Figure 3 showing the mounting means as turned to permit removal of the blade from the jaw;

Fig. 5 is a side elevation of the mounting pin;

Fig. 6 is a detail enlarged view of the relation of the pin and the mounting portion of the work engaging blade showing in full lines the blade in position to be removed from the jaw, while showing in dotted lines the blade in its working position.

In the use of tenter chain links, it is desirable to have a rockably mounted work engaging blade in the movable jaw so that the same will adjust or position itself on the sur-

face of the fabric to obtain the best biting engagement between it and the fixed jaw. The work engaging blade is sharpened so that its edge will better bite the fabric, and from time to time it is desirable to remove the blade for replacement or resharpening the edge thereof, and in order that this may be easily accomplished, I have provided a pin which extends through an opening in the blade located in the middle part thereof for pivotally mounting the blade in the jaw, the blade having a constricted entrant notch extending from the edge of the blade to this opening through which a narrowed portion of the pin may extend, the pin being rotatably mounted to move this narrowed portion as desired from working to inoperative position; and the following is a detailed description of the present embodiment of this invention illustrating the preferred means by which these advantageous results may be accomplished.

With reference to the drawings, 10 designates the body of the tenter chain link which is provided with the usual spaced ears 11 and 12 at one end to receive a single ear 13 of the next link which is at the opposite end of each link from the spaced ears 11 and 12. A fixed jaw 14 is provided on the body and an overhanging portion 15 pivotally mounts the swinging or movable jaw 16 above the fixed jaw 14. The movable jaw is hingedly supported upon a pin 17 which extends through the bearings 39 and 40 on the overhanging portion and the bosses 18 and 19 and the opener member 20 of the movable jaw. The lower portion of the movable jaw is provided with a recess 21 extending across the width thereof and shaped as illustrated in Figures 3 and 4 with an arcuate portion 22 at its middle. Within this recess 21 there is located a work engaging blade 23 provided with an arcuate portion 24 which is received within the arcuate portion 22 of the recess. A generally circular opening 25 is

provided in the blade located partially in the arcuate area at the upper edge of the blade and a constricted entrant opening or notch 26 leads from the opening 25 to the edge of 5 the blade.

A boss or enlargement 28 is provided on the face of the movable jaw, a pin 27 is rotatably mounted in this boss and spans the recess 21 therein. This pin 27 is slotted or cut away 10 as at 29 within the recess to reduce its cross section sufficiently to permit it to pass through the constricted entrant opening 26 in the edge of the blade when the pin is rotated to one certain position.

15 In mounting the blade in the jaw, the pin 27 is rotated to the position shown in Figure 4 by a screw driver or the like which will be used for engaging the slot 30 thereof for this purpose, the same being positioned to 20 aligning the slot with a mark or other designation 31 on the face of the boss 28, and after the blade is positioned, the pin is rotated in a similar manner a quarter of a turn to cause the slot 30 to align with the mark or other 25 designation 32, thus bringing the pin to the position illustrated in Figure 3 to pivotally and positively support the blade in position.

There is no spring action or the like permitting the blade to be withdrawn by appropriate pull, but rather the same is positively mounted in position. In order to positively lock the pin in working position, an opening 33 is provided through the pin and also an opening 34 is provided in the boss 28 and 30 when the pin has its slot 30 aligned with the indica 32 the openings 33 and 34 will align for the reception of the lock pin 35 which may be of the cotter pin type to have its end portions 36 bent over to hold the same in 35 position, as illustrated in Figure 1.

It will be apparent that I have provided a construction in which the blade may be easily removed for repair or replacement by simple manual manipulation of a pin, and yet when 40 in working position, the same is positively held against removal and yet pivotally or rockably supported in position by a single suitably shaped pin.

While I have described certain construction forms which embody the principles of my invention, it is obvious that other desired changes in arrangement may be made within the spirit and the scope of the invention as defined in the appended claims.

55 I claim:

1. In a tenter chain link, a movable jaw having a slot therein, a work engaging blade in said slot having an opening therein, and means extending through said opening shift- 60 able in said opening without removal therefrom for positively and removably holding said blade in said slot.

2. In a tenter chain link, a movable jaw having a slot therein, a work engaging blade 65 in said slot having an opening therein with

a constricted entrance to said opening from the edge thereof, and means movably mounted in said jaw to be passed through said entrance when in one position, but prevented from removal from said opening when in 70 another position.

3. In a tenter chain link, a movable jaw having a slot therein, a work engaging blade in said slot having an opening therein with a constricted entrance to said opening from 75 the edge thereof, and a pin rotatably mounted in said jaw substantially the size of said opening and having a flattened side to permit it to be removed from said constricted entrance.

4. In a tenter chain link, a movable jaw having a slot therein, a work engaging blade in said slot having a circular opening therein with a constricted entrance to said opening from 80 the edge thereof, and a cylindrical pin rotatably mounted in said jaw substantially the size of said opening located therein to pivotally mount the blade in the jaw and having a flattened side to permit it to be removed from said constricted entrance. 85

5. In a tenter chain link, a movable jaw having a slot therein, a work engaging blade in said slot having an opening therein with a constricted entrance to said opening from 90 the edge thereof, a pin rotatably mounted in said jaw substantially the size of said opening and having a flattened side to permit it to be removed from said constricted entrance, and means to prevent rotation of said pin. 95

6. In a tenter chain link, a movable jaw 100 having a slot therein, a work engaging blade in said slot having an opening therein with a constricted entrance to said opening from the edge thereof, a pin rotatably mounted in said jaw substantially the size of said opening and having a flattened side to permit it to be removed from said constricted entrance, a boss on said movable jaw having an opening therethrough; said pin having an opening registering with said opening in said boss, and a pin extending through said registering openings. 110

7. In a tenter chain link, a movable jaw having a slot therein, a work engaging blade in said slot having an opening therein with 115 a constricted entrance to said opening from the edge thereof, and a pin rotatably mounted in said jaw substantially the size of said opening and having a flattened side to permit it to be removed from said constricted entrance, said pin having a slotted head for rotation. 120

8. In a tenter chain link, a movable jaw having a slot therein, a work engaging blade in said slot having an opening therein with 125 a constricted entrance to said opening from the edge thereof, a pin rotatably mounted in said jaw substantially the size of said opening and having a flattened side to permit it to be removed from said constricted entrance. 130

trance, and means for designating the location of the flattened portion of said pin in different positions of rotation.

9. In a tenter chain link, a movable jaw
5 having a slot therein, a work engaging blade
in said slot having an opening therein with
an entrance to said opening from the edge
thereof and means movably mounted in said
jaw to be passed through said entrance when
10 in one position, but prevented from removal
from said opening when in another position.

In testimony whereof I affix my signature.
WILLIAM A. STELLING.
